UNITED STATES PATENT OFFICE.

JOHN S. McWHIRTER, OF NEW YORK, N. Y., ASSIGNOR TO WESTINGHOUSE ELECTRIC & MANUFACTURING COMPANY, A CORPORATION OF PENNSYLVANIA.

CONTROL APPARATUS.

Application filed June 9, 1919. Serial No. 302,665.

To all whom it may concern:

Be it known that I, JOHN S. McWHIRTER, a citizen of the United States, and a resident of New York, in the county of New York and State of New York, have invented a new and useful Improvement in Control Apparatus, of which the following is a specification.

My invention relates to control apparatus for dynamo-electric machines and particularly to platform controllers for electric railway motors.

One object of my invention is to provide a controller that may be selectively operated either by the hand or some other suitable portion of the motorman's body, or by a power device.

Another object of my invention is to provide a combined apparatus of the above-indicated character wherein the operating handle is not actuated by movement of the power device but is adapted to effect operation of the controller when subjected to pressure of the motorman's hand.

A further object of my invention is to provide control apparatus for platform controllers whereby either foot or hand operation thereof may be selectively employed.

Other objects of my invention, directed toward flexibility of operation and simplicity and reliability of construction, will become evident from the following detailed description, taken in conjunction with the accompanying drawing, wherein

Figure 1 is a view, chiefly in section, but partly in elevation, of a complete control apparatus constructed and arranged in accordance with my present invention;

Fig. 2 is a top plan view, taken along the line II—II of Fig. 1; and

Fig. 3 is a diagrammatic view of an auxiliary control system that may be employed in carrying out my invention.

Referring to Fig. 1, the structure here shown comprises a platform controller of the familiar "K" type, embodying a main-circuit control drum 2 having an operating shaft 3 extending upwardly through the controller cover, and a main reverser drum 4 that is provided with an operating shaft

5, to the outer end of which is attached the familiar reverse lever 6.

The apparatus further comprises a power device 7, of a familiar electrically-controlled pneumatically-operated type, for actuating the main control drum 2 when desired, and a hand-operated device 8 for selectively actuating the control drum 2 when manual operation is desired. A foot-operated controller 9 co-operates with the power device 7 in a manner to be set forth, so that, in one aspect, my invention provides selective hand-or-foot-control operation.

It should be understood that, for the sake of clearness, I have illustrated my operating mechanism on a larger scale than is actually employed in practice, and, in reality, the entire hand-and-power-operated mechanism would not require operating space in a horizontal plane larger than the area of the controller cover.

The power device 7 comprises a power-transmitting member or pinion 12 which is slidably mounted upon the shaft 3 of the main control drum 2 and is provided with a hub 13 to act as a core for a coil 14 that is connected in circuit with the control drum 2 and with the railway motors or other apparatus to be controlled. The purpose of the coil 14 will be set forth later. A suitable helical spring 15 encloses the shaft 3, the lower end thereof resting upon the controller cover and the upper end bearing against the hub 13 of the pinion 12 to bias the pinion upwardly to a position of meshing engagement with a transversely movable rack or power-transmitting member 16. A plate or disk 17, having a plurality of upwardly extending tongues or ridges 18, is secured to the upper face of the pinion 12 for the purpose of engagement with the hand-operated device 8, as hereinafter set forth. To limit the upwardly biasing movement of the spring 15 upon the pinion 12, a cotter-pin 19, or the like, extends through the upper end of the shaft 3 between the tongues 18 of the plate 17. Furthermore, a suitable key or spline 20 is provided to prevent rotative movement of the pinion 12 relative to the control shaft 3.

The ends of the rack member 16 respectively constitute pistons 21 and 22 that travel within suitable operating cylinders 23 and 24. A normally closed valve 25 is provided with an actuating coil "On" which, when energized, actuates the valve to admit fluid pressure from any suitable source (not shown) through a supply pipe 26 to the cylinder 23. On the other hand, the cylinder 10 24 communicates with a normally open valve 27 that initially places the cylinder 24 in communication with a supply pipe 28. An actuating coil "Off" is provided for cutting off this communication and exhausting fluid 15 pressure from the cylinder 24 to the atmosphere.

The wires or conductors for the valve magnets "On" and "Off" may be housed in any convenient manner and are here 20 shown as respectively connected to suitable junction boxes 29 and 30, a conduit 31 joining the junction boxes and a second conduit 32 leading to the control box 33 of the foot-operated controller 9. This drum-type controller is provided with an operating shaft 34 to which a pedal or foot lever 35 is secured, for the purpose of effecting the operation of the controller and, therefore, the actuation of the power device 7, 25 as described later in connection with Fig. 3.

The hand-operated device 8 comprises a disk or plate type of clutch member 36 that is provided with a plurality of grooves or notches 37, which are located in a complementary sense with respect to the tongues or ridges 18 of the plate 17. The disk 36 is rigidly mounted upon a shaft or rod 38 to which is slidably keyed a sleeve member 39 having a laterally extending arm 40. An operating lever 41 is pivotally secured to the arm 40, and an intermediate portion of the lever rests upon the upper end of the rod 38. The lever 41 is provided with the familiar grip 42 for effecting manual operation of the controller. A coil spring 43 is positioned within a recess in the upper face of the sleeve 39, to enclose the rod 38 and to bear against a pin or disk 44 that is positioned near the upper end of the rod for the purpose of normally maintaining the plate 36 out of engagement with the cooperating disk 17, as illustrated. For the purpose of suitably supporting the hand-operated device 8, a bent arm 45 has one apertured end loosely enclosing the sleeve 39, the lower end of the arm 45 being suitably secured to the controller cover.

Assuming that the various parts occupy the positions shown and that it is desired 60 to effect operation of the control drum 2 by means of the power device 7, such operation may be set forth as follows, reference being had to Fig. 3, also. Upon movement of the pedal or foot lever 35, the associated controller, which is preferably provided

with operating positions *a* and *b*, is actuated to effect energization of the coils "On" and "Off," in accordance with the following circuits, assuming that the foot-operated controller has been actuated to its position *b*. One such circuit is established from the positive terminal of a battery B, or other suitable source of energy, through conductor 50, control fingers 51 and 52, which are bridged by contact segment 53 of the foot-operated controller 9, whence circuit is completed through conductor 54, actuating coil "On" and conductors 55 and 56 to the negative battery terminal.

A further circuit is continued from the contact segment 53 through control finger 57, conductor 58, actuating coil "Off" and conductor 59, to the negative conductor 56.

Since both actuating coils "On," and "Off" are concurrently energized, movement of the pistons 21 and 22 towards the right and, therefore, of the control drum 2 in a clockwise direction, viewed from above, occurs by reason of the fact that fluid pressure is admitted to the cylinder 23 through the opened valve 25 and is exhausted from the cylinder 24 through the closed valve 27, thus reversing the initial unbalanced condition of fluid pressures in the power device 7.

To arrest such movement at any time, it is merely necessary to return the foot-operated controller 9 to its position *a*, whereby the "Off" coil is de-energized, and balanced high fluid-pressure conditions, therefore, obtain in the power device 7 to effect a positive and reliable stoppage thereof.

It will be understood that, if desired, other well-known expedients for effecting step-by-step movement of the power device 7 may be employed, such as a limit switch or current relay that is actuated in accordance with the current traversing the car-propelling motors or other apparatus to be controlled, and is adapted to govern the energization of the "Off" coil. The simple system shown in Fig. 3, however, is believed to disclose the principle of foot control of the power device 7 sufficiently for the purposes of the present specification.

To produce a return movement of the control drum 2, the pedal 35 may be returned to its initial position, either by movement of the operator's foot or by a suitable biasing spring, whereupon both actuating coils "On" and "Off" are concurrently de-energized to cause fluid-pressure conditions in the power device 7 to revert to the original unbalanced condition and thus effect the desired backward movement.

Whenever manual operation of the control drum 2 is required for any reason, the handle grip 42 is depressed, in opposition to the action of the coil spring 43, to cause engagement of the plates or disks 36 and 17.

Such depression of the handle member further forces the pinion 12, in opposition to the action of the spring 15, out of engagement with the rack member 16 and, since the plates 17 and 36 are of smaller diameter than the pinion 12, the rack member 16 is entirely free from contact with any portion of the hand-operated apparatus. Consequently, rotative movement of the handle member 42 primarily effects similar movement of the rod 38, which is keyed to the sleeve 39 and, therefore, of the engaging plates 36 and 17 and of the free-running pinion 12 which is keyed to the control-drum shaft 3.

In this way, step-by-step manual control in accordance with the desires of the motorman may be effected and, even though the foot-operated controller 9 should accidentally or otherwise be actuated, no interference with the hand-operated movements in question can occur, by reason of the fact that the rack member 16, as previously mentioned, is entirely free from contact with any of the rotatable elements of the apparatus.

Furthermore, should the motorman release his downward pressure upon the handle grip 42, for any reason, during the operation of the controller, the pinion 12 will not be returned by the biasing spring 15 to its illustrated position, which would effect improper relative meshing position of the pinion and the rack, because of the fact that the coil 14 which, as mentioned above, is energized by the current of the car-propelling motors, maintains the pinion 12 in its depressed position as long as the control drum 2 occupies any operative position. Although the coil 14 will thus maintain the pinion 12 in such depressed position under the conditions stated, the magnetic attraction thereof is insufficient to pull the pinion 12 down to that position, whereby improper movement of the pinion 12, when the power device 7 is being actuated, is prevented.

It will be seen that I have thus provided actuating apparatus for platform controllers or the like which may be selectively operated either by hand or by power or, from another aspect, either by foot or by hand control. It should be understood, however, that other types and arrangements of body-operated devices may be employed, if desired.

I do not wish to be restricted to the specific structural details, circuit connections or arrangement of parts herein set forth, as various modifications thereof may be made without departing from the spirit and scope of my invention. I desire, therefore, that only such limitations shall be imposed as are indicated in the appended claims.

I claim as my invention:

1. The combination with a movable control member, of a body-operated member, a power-actuated member normally connected

to the control member to operate it in both directions, and means for effecting selective operation of said control member including a connection of either said body-operated member or said power-actuated member alone to said control member.

2. The combination with a rotatable control drum, of a body-operated member, a power-actuated member biased to connection with said control member in both directions of operation, and means for normally preventing concurrent use of said members.

3. The combination with a movable switching device, of a power-actuated member for normally operating said switching device in either direction, and means dependent upon body pressure for effecting hand operation of said device and concurrently preventing such operation by said power-actuated member.

4. The combination with a movable switching device, of a fluid-pressure actuated member for normally operating said switching device, and normally independent means for preventing such operation and concurrently effecting body operation of said device.

5. The combination with a movable control member, of power-actuated means therefor, a plurality of power-transmitting members normally interposed between said means and said control member in either direction of operation, and body-operated means for effecting relative inoperativeness of said power-transmitting members and direct operation of said control member.

6. The combination with a rotatable switching device, of a toothed member rotatable therewith, a second toothed member normally meshing with the other toothed member, power means for actuating said second toothed member, and hand-operated means for effecting disengagement of said toothed members and operation of said switching device under predetermined conditions.

7. The combination with a rotatable control drum, of a pinion rotatable therewith and slidable with respect thereto, a rack member normally meshing with said pinion, fluid-pressure-operated means for actuating said rack member, and independent means responsive to manual pressure for effecting disengagement of said pinion from said rack member and hand operation of said drum.

8. The combination with a movable control member, of means operable to effect manual actuation of the control member, means adapted to effect power actuation of the control member and means cooperative to maintain continuously connection between either of said actuating means and the control member.

9. In a controller, in combination, a movable control member, manual means operable to effect the operation of the control mem-

- ber, power means adapted to operate the control member, means disposed to effect a connection between said power means and control member and means disposed to connect said manual means to the control member, each connecting means being adapted to maintain the connection.
10. The combination with a movable control element, of a power-actuated member 10 biased to connection with said element in both directions of operation, body-operated means for actuating said element independently of said power-actuated member, and other body-operated means for governing said power-actuated member independently of the first-named body-operated means to move said control element.
11. The combination with a rotatable control drum, of a fluid-pressure-operated member, electrical means for governing said member, body-operated means for actuating said drum independently of the fluid-pressure-operated member, and other body-operated means for controlling said electrical 25 means independently of the first-named body-operated means to move said control drum.
12. The combination with a movable control member, of means operable to effect 30 manual actuation of the control member, means adapted to effect power actuation of the control member, means adapted to connect either actuating means to the control member, and means adapted to maintain continuously either of said connections.
13. The combination with a rotatable control drum, of a fluid-pressure-operated member, electrical means for governing said member, hand-operated means for actuating 40 said drum independently of the fluid-pressure-operated member, and foot-operated means for controlling said electrical means independently of the hand-operated means to move said control drum.
45. 14. In a controller, in combination, a movable control member, means operable to effect manual actuation of the control member, means adapted to effect power actuation of the control member, means disposed for operation to connect either actuating means to the control member and electrically-controlled means adapted to maintain one of said connections.
55. 15. The combination with a movable switching device, of a fluid-pressure-actuated member for normally operating said device, a foot-operated member for governing said fluid-pressure-actuated member, and a normally independent hand-operated member for preventing such normal operation and concurrently effecting manual operation of said device.
60. 16. The combination with a movable control member, of power-actuated means therefor, a plurality of power-transmitting mem- bers normally interposed between said means and said control member, a foot-operated means for governing said power-actuated means, and hand-operated means for effecting relative inoperativeness of said power-transmitting members and operation of said control member.
70. 17. The combination with a rotatable switching device, of a toothed member rotatable therewith, a second toothed member normally meshing with the other toothed member, power means for actuating said second toothed member, foot-operated means for governing said power means, and hand-operated means for effecting disengagement of said toothed members and operation of said switching device under predetermined conditions.
75. 18. The combination with a rotatable control drum, of a pinion rotatable therewith and slidable with respect thereto, a rack member normally meshing with said pinion, fluid-pressure-operated means for actuating said rack member, foot-operated means for governing said fluid-pressure-operated means, and independent means responsive to manual pressure for effecting disengagement of said pinion from said rack member and hand operation of said drum.
80. 19. In a controller, in combination, a movable control member, means operable to effect manual actuation of the control member, means adapted to effect power actuation of the control member, means disposed for operation to connect either actuating means to the control member and electrically-controlled means adapted to maintain one of said connections, said electrically-controlled means being adapted for release when the movable control member is moved to its 100 "off" position.
85. 20. In a controller, in combination, a movable control member, means operable to effect manual actuation of the control member, means adapted to effect power actuation of the control member, means disposed for operation to connect either actuating means to the control member, electrically-controlled means to maintain one of said connections and mechanical means disposed to maintain the other of said connection, said electrical and mechanical means being balanced thereby to permit the continual maintenance of either connection until the development of predetermined operating conditions.
105. 21. The combination with a rotatable control drum, of a pinion rotatable therewith and slidable with respect thereto, a rack member, a spring for normally biasing said pinion to engagement with said rack member, fluid-pressure-operated means for actuating said rack member, and a hand-operated clutch member biased to an independent position for effecting disengagement of said pinion from said rack member and rota-
110. 115. 120. 125. 130.

tive movement of said drum upon the application of manual pressure to said clutch member.

22. In a controller, in combination, a movable control member, means operable to effect manual actuation of the control member, means adapted to effect power actuation of the control member and means dis-

posed for operation to connect either actuating means to said control member, said connecting means being balanced thereby to maintain the connection established.

In testimony whereof, I have hereunto subscribed my name this 16th day of May, 1919.

JOHN S. McWHIRTER.
